UNITED STATES PATENT OFFICE.

JOHN F. O'CONNOR, OF CHICAGO, ILLINOIS, ASSIGNOR TO WILLIAM H. MINER, OF CHAZY, NEW YORK.

ROCKER SIDE BEARING.

1,357,799.

Specification of Letters Patent. Patented Nov. 2, 1920.

Application filed January 20, 1919. Serial No. 271,944.

To all whom it may concern:

Be it known that I, JOHN F. O'CONNOR, a citizen of the United States, residing at Chicago, in the county of Cook and State 5 of Illinois, have invented a certain new and useful Improvement in Rocker Side Bearings, of which the following is a full, clear, concise, and exact description, reference being had to the accompanying drawings, 10 forming a part of this specification.

This invention relates to improvements in rocker side bearings.

One object of the invention is to provide a rocker side bearing more particularly 15 adapted for railway cars and which is arranged to be secured to the body bolster, the rocker being freely suspended and adapted to return to central or normal position under the influence of gravity upon 20 release of the actuating pressure.

Another object of the invention is to provide a rocker bearing of the type above indicated wherein the rocker is bodily movable with respect to its housing and yet so 25 arranged that it cannot be displaced by jar- 30 ring or vibration from its normal position beyond a predetermined limited amount, the permissible limited amount of displacement being so restricted that the rocker will 35 be in condition to function through an arc substantially as great as if in its central normal position.

In the drawings forming a part of this specification, Figure 1 is a vertical, sec- 35 tional view taken transversely through the ends of the truck and body bolsters of a car and showing my improvements in connec- 40 tion therewith. Fig. 2 is a horizontal, sec- 45 tional view taken substantially on the line 2—2 of Fig. 1. Fig. 3 is a vertical, sectional view taken substantially on the line 3—3 of Fig. 1. Fig. 4 is a view similar to Fig. 1 but illustrating a somewhat different em- 50 bodiment of the invention. And Fig. 5 is a vertical, sectional view taken substantially on the line 5—5 of Fig. 4.

In said drawing, 10 denotes the upper sec- 55 tion of a truck bolster and 11 the lower section of an opposed body bolster and be- tween which my improved rocker bearing is 60 adapted to be employed. The bearing, as shown, comprises broadly, a housing A, a wear or thrust plate B, a rocker C, a pair of plates D—D and a pair of disks E—E. 65

The housing A is of substantially hollow

rectangular formation having end walls 12—12 and side walls 13—13. The housing is preferably in the form of a casting open at top and bottom and is provided with suitable lugs 14 by which it can be secured to the body bolster. At the top on its interior, the housing A is provided with ledges 15—15 arranged to hold the plate B against the body bolster, as clearly shown in Fig. 1. The plate B may have a 65 steel insert 16 to take the direct pressure of the rocker, as will be understood. The side walls 13 of the housing are formed with inwardly extending flanges 17 at their lower edges, as clearly indicated in Fig. 3, said 70 flanges forming supporting ledges for the plates D and disks E.

The rocker C has an upper curved bearing surface 18 concentric with but of shorter radius than the lower curved bearing sur- 75 face 19. The two bearing surfaces 18 and 19 are joined by flat faces 20 preferably ar- ranged tangential to the upper bearing sur- 80 face 18. At each end, the rocker C is pro- vided with trunnions 21 arranged concen- 85 tric with the upper bearing surface 18. To lessen the amount of metal required for the rocker, the same may be cored, as indicated at 22 and 23.

Each plate D is of generally triangular 85 formation having a lower horizontal edge 24 and inclined edges 25—25. There are relatively short vertical end edges 26—26 and also a horizontal top edge 27. On the face of each plate D adjacent the rocker, 90 there are provided vertical flanges 28—28 spaced apart a distance corresponding to the diameter of the trunnions of the rocker and the latter are seated within the guid- 95 ways formed by the flanges 28 as apparent from an inspection of Figs. 1 and 2.

Each of the disks E is of the same di- 100 ameter as the trunnions 21 and are equal in thickness substantially to the distance which the trunnions are extended from the body of the rocker C. The disks E, as clearly shown in Figs. 1 and 3, are also seated within the guideways formed by the flanges 28 of the plates D and the disks roll upon the flanges 17 of the housing. 105

The operation is as follows: Assuming the rocker bearing to be brought into play when the rocker is in normal position and the body bolster remaining stationary while the truck bolster moves to the right, as viewed 110

in Fig. 1, it is evident that the rocker will assume the dotted position shown in Fig. 1. During this movement, it is evident that the common center of the bearing surfaces 18 and 19 and of the trunnions 21 will move horizontally a comparatively short distance. This movement of the rocker will force the plates D toward the right hand end of the housing A until the plates D assume the dotted position also shown in Fig. 1. The disks E will naturally travel with the plates D. In this connection, it may be added that the end walls of the housing A are preferably provided with inwardly projecting shoulders 30—30 formed on their under sides to correspond with the rocker and limit the upward movement thereof. If now the pressure on the rocker bearing is relieved, the rocker will naturally tend to swing back to a state of equilibrium and the weight thereof will be transferred through the trunnions 21 onto the disks E, and as the trunnions are rotated by the swinging movement of the rocker, the rotative movement will be communicated to the disks E and the latter will roll along the supporting flanges 17, thus bringing the plates D, rocker and disks E back to their original position since the diameters of the disks E and trunnions 21 are equal. As will be understood from the preceding description when considered in connection with Figs. 1 and 3, the rocker is normally slightly separated from the upper bearing plate so as to permit the return movement above described.

By referring to Fig. 1, it will be noted that there is a relatively small space between the vertical edges 26 of the plates D and the end walls of the housing A. Because of this, it is impossible for the plates D to be shifted from normal position by jarring or vibration more than the space between a vertical edge 26 and adjacent end wall. Even though this amount of displacement should occur from vibration and while the rocker is not being actuated, nevertheless if the rocker is brought into play when the plates D are displaced to their maximum, the rockers will still have a permissible swinging movement only slightly less than the permissible movement from the central normal position of the rocker. With this arrangement, it is impossible to displace the rocker to an amount where it will not properly function.

In the construction shown in Figs. 4 and 5, the arrangement of housing A', plate B' and rocker C' is the same as in Figs. 1, 2 and 3. Instead of employing the plates D, however, I may employ two elongated bars D'—D' having studs 31 on which are rota-

tably mounted two disks E', the latter being of the same diameter as the studs on the rocker. In this construction, as in the construction first described, the bars D' are limited in the amount of possible displacement so that the rocker will always function. When the rocker has been actuated to the position indicated by dotted lines in Fig. 4, it is evident that the return swinging movement of the rocker will be communicated to all four disks E' and the latter together with the bars D' returned to their original position as in the case of the plates D.

I claim:

1. In a rocker side bearing, the combination with a housing adapted to be secured to a body bolster, of a rocker within said housing having upper and lower concentric bearing surfaces of different radii, trunnions formed on the ends of said rocker concentric with the upper bearing surfaces thereof, members within said housing and supported by the latter, said members being movable lengthwise of the housing, and means for translating oscillating movement of said rocker to lineal movement of said members, said means including rotatable disks coöperable with the trunnions of the rocker.
2. In an anti-friction bearing of the character described, the combination with a hollow housing having depending side walls each of which is provided at its lower edge with a longitudinally extending ledge; of members lineally slidably back and forth on said ledges, said members being provided on their inner faces with guiding grooves; a rocker having trunnions at its ends extending within and coöperating with said grooves; and rolling supporting elements for said trunnions sustained on said ledges.
3. In an anti-friction bearing of the character described, the combination with a hollow substantially rectangular housing adapted to be secured to the under side of a body bolster or the like, the side walls of said housing being provided at their lower edges with horizontally extending ledges; of a member lineally slidably mounted on each of said ledges, each of said members having a vertically extending groove therein on its inner face; a disk supported on each ledge and disposed within one of said grooves; and a rocker having trunnions at the top thereof at each end, said trunnions extending within said grooves and supported on said disks.

In witness that I claim the foregoing I have hereunto subscribed my name this 2nd day of Jan. 1919.

JOHN F. O'CONNOR.
